UNITED STATES PATENT OFFICE.

EMIL JAGENBERG, OF DUSSELDORF, GERMANY.

PROTECTIVE COVER FOR ROLLS OF PAPER AND THE LIKE.

1,091,139.

Specification of Letters Patent. Patented Mar. 24, 1914.

Application filed July 30, 1913. Serial No. 781,909.

To all whom it may concern:

Be it known that I, EMIL JAGENBERG, manufacturer, a subject of the German Emperor, and resident of 107 Himmelgeisterstrasse, Dusseldorf, Germany, have invented certain new and useful Improvements in Protective Covers for Rolls of Paper and the like, of which the following is a specification.

Hitherto rolls of paper and the like were protected against damage during transport by means of several layers of packing paper wrapped around such rolls. These layers of packing paper were glued together, so that they formed a protective sheath on the surface of the roll, or, particularly with large rolls, they were held by strips of sheet metal, which were secured close to the edges. These known provisions for protecting paper rolls are, however, very insufficient, as they will protect the circumferential surface of the rolls only against damage, but not the face ends, and least of all the edges, which suffer most during transport. The strips of metal laid around the rolls at the edges are of no avail, on the contrary, they will even be harmful, as their sharp edges penetrate into the paper web, and when they are detached, they will easily tear the paper. A large number of layers of the paper will be useless, whereby a considerable wastage is caused.

The present invention relates to a protective cover for paper rolls and the like, by which the troubles hereinbefore stated are avoided, as the new cover will protect the outer face as well as both ends and the edges of the roll against all damages, and may, besides, be easily applied and removed, without giving rise to any injury to the paper web.

The present invention is exemplified in the accompanying drawing.

Figure 1 is a perspective view of the same. Fig. 2 is a side view, partly in section. Fig. 3 is a sectional view on an enlarged scale, and Fig. 4 is a modification in a perspective view.

The roll of paper or the like *a* is wrapped in several layers of a web of packing paper *b*, the width of which is greater than that of the paper to be covered. This cover *b* will therefore project at both ends of the rolls to a more or less great extent. While the packing paper is being wrapped around the roll,

such packing paper is coated in known manner with a layer of an adhesive, so that the several layers will be thereby glued together. After the packing paper *b* has been thus wrapped around the roll, the projecting ends are folded down in any suitable manner and pressed close against the ends of the roll. If it is deemed advisable, circular disks of pasteboard or paper *d* may be laid against the ends of the rolls previous to such folding down of the ends of the wrapper. By such means annular flanges of any desired width and formed of a plurality of folds can be produced, and these flanges *f* will, after the adhesive has hardened and the folds have thus become fixed, form very hard and strong protective angular covers *g* at the corners. These strong, crustlike covers *g* will completely incase the edges of the roll and protect them against their being injured. The disks *d* will prevent the adhesive from entering into the paper web, when the flanges *f* are pressed down against its ends.

If the roll *a* consists of a web of smooth paper, the wrapper of packing paper *b* is made of such a width that when the projecting ends are turned down and pressed against the ends of the roll, the latter are almost completely or completely covered (Fig. 4). After the adhesive has dried, the roll will become incased on its face as well as on its ends within an extremely stiff sheath, which protects the web against injury, and also prevents the inner coils from slipping endwise out of the outer coils. A wire or cord *h* may be embodied in the sheath, by means of which the sheath can be easily torn open for removing it.

I claim:

A paper roll, provided with a cover that extends over the face of the roll and is provided with a pair of inwardly turned flanges that extend over the ends of the roll, each of said flanges being formed of a plurality of folds, and with a hardening adhesive carried by the cover, and adapted to stiffen the flanges and fix the folds thereof.

In testimony whereof I hereto affix my signature in the presence of two witnesses.

EMIL JAGENBERG. [L. S.]
